UNITED STATES PATENT OFFICE.

ALBERT A. HUTCHINSON, OF WINCHESTER, MASSACHUSETTS.

HIDE-WORKING MACHINE.

SPECIFICATION forming part of Letters Patent No. 781,775, dated February 7, 1905.

Application filed February 8, 1904. Serial No. 192,662.

To all whom it may concern:

Be it known that I, ALBERT A. HUTCHINSON, a citizen of the United States of America, and a resident of Winchester, in the county of Middlesex and State of Massachusetts, have invented certain new and useful Improvements in Hide-Working Machines, of which the following is a specification.

This invention relates to hide-working machines, and has for its object the production of a machine in which the supporting cylinder coöperates with a rubber-covered roll whereby the hide may be spread or worked out much more readily than in machines now in common use.

It further provides for a hide-support consisting of a bed-roll and a hide-supporting roll mounted in pivoted frames which are adapted to be moved about their pivots to bring the bed-roll and working cylinder in coöperating position.

Another object is to provide a simple mechanism for revolving the hide-supporting roll in opposite directions when the bed-roll is coöperating with the working cylinder and when it is not.

Furthermore, provision is made by this invention for a means for moving the bed-roll support about its fulcrum to bring the bed-roll and working cylinder into contact without the use of springs or other devices liable to become inefficient, and, finally, a device is provided which forms one of the principal features of the invention, whereby a radius-arm secured to the hide-support is made to coöperate with a fixed cam to force said hide-support into position to coöperate with the working cylinders and hold the same in such position without strain upon the operator.

It consists in certain novel features of construction and arrangement of parts, which will be readily understood by reference to the description of the drawings and to the claims to be hereinafter given.

Of the drawings, Figure 1 represents a front elevation of the left-hand side of a machine embodying this invention. Fig. 2 represents a left end elevation of the same. Fig. 3 represents a similar view with the driving-gear

cut away, the cutting-plane being on line 3 3 50 on Fig. 1. Fig. 4 represents a transverse vertical section of the same, the cutting-plane being on line 4 4 on Fig. 1. Fig. 5 represents a sectional plan of the driving mechanism. Fig. 6 represents a sectional elevation of the fixed cam, the end of the coacting radius-arm, and the means for operating said radius-arm; and Fig. 7 represents a perspective view of a portion of the rocker-frame, secondary frame, and adjacent parts looking from the rear of 60 the machine.

Similar characters designate like parts throughout the several figures of the drawings.

To support the working parts of the machine, a main frame is preferably provided, made up of end frames 10 10 and tie-girths 11 11. In the frames 10 is mounted a shaft 12, and in the left-hand frame is mounted a short stud 13. The shaft 12 extends beyond the 70 left-hand frame, and upon this and the stud 13 is secured a plate 14, which is provided with short studs 15 16 17. On the studs 15 and 16 are mounted long-toothed gears 18 and 19, meshing together. The gear 18 is driven 75 by a spur-gear 20, secured thereto and meshing with a pinion 21 on the stud 17. This pinion 21 is driven by a driving-pulley 22, keyed thereon.

On the shaft 12 outside of the frames 10 are 80 pivoted rocker-levers 23, having provided in the free ends thereof bearings 24 for trunnions 25 of the side or secondary frames 26. These side frames 26 are provided with bearings 27, in which is mounted a hide-supporting roll 28, the left-hand trunnion 29 of which has secured thereto a long-toothed gear 30, adapted to mesh with the gears 18 19 and which is driven therefrom. The driving-pulley 22 is driven continuously in the direction indicated by the arrows on Fig. 2, and it is obvious that the gears 18 19 are thereby driven in opposite directions. When the rocker-lever 23 is in the position shown in Fig. 2, in which position it is adapted to receive a hide, the gear 30 meshes with the gear 19 and is driven thereby in a direction indicated by the arrows on Fig. 2 to revolve the

hide-supporting roll in a direction to feed the hide into position to be operated upon by the working cylinder 31.

On the trunnions 29 of the hide-supporting roll are mounted arms 32, in the free ends of which is mounted a rubber-covered bed-roll 33. This bed-roll 33 is mounted in suitable boxes 34 in the frame 32, and said boxes 34 are controlled by suitable tension devices 35, 10 of ordinary construction, tending to keep said bed-roll in contact with the working cylinder 31 when said bed-roll and cylinder are coöperating. The side frames 32 are adjustably connected at 36 to the secondary frames 26.

15 Above and to the rear of the hide-supporting rolls 28 are mounted in suitable boxes 37 38 the feed-rolls 39 40. The boxes 37 38 are provided with suitable spring-tension devices forcing said feed-rolls into position to coöperate with the hide-supporting roll 28. The working cylinder 31 is mounted on a shaft 41, upon which is a driving-pulley 42, by which said working cylinder may be driven at any desired speed.

20 25 To the outer ends of the rocker levers or frames 23 are pivoted radius-arms 43, the opposite ends of which are forked, as at 44, and provided with a pin 45, on which is mounted rollers 46. The pin 45 extends through a slot 47 in an arm 48, keyed to a shaft 49, upon which is secured a treadle 50, by which said arm 48 is operated.

To the side frames 10 are secured cam-plates 51, with which the rolls 46 coöperate.

30 35 The normal position of the rocker levers or frames 23 is as shown in Fig. 2, the treadle 50 being in its uppermost position, the rollers 46 being at their extreme rear position, the hide-supporting roll 28 being at its extreme forward position, and the hide-supporting-roll-operating gear 30 being in mesh with the gear 19 and revolving in the direction indicated by the arrows to feed the hide into position to be operated upon by the working cylinder 31. When a little more than one-half of the hide has been fed into position, so that the center of the hide is just below the working cylinder, the operator places his foot upon the treadle 50, and the slotted portion of the arm 48 operates against the pin 45 and forces the lower end of the radius-arm 43 toward the front of the machine into the position shown in dotted lines in Fig. 4, causing the rocker-levers 23 to move about their pivots toward the working cylinder 31. During this operation the radius-arms 52, secured at 53 to the side frames 10 and the opposite ends of which are pivoted at 54 to the arms 55, projecting downwardly from the side or secondary frames 26, change 40 the inclination of said side frames, so that the hide-supporting roll 28 is brought into position to coöperate with the feed-rolls 39 40, and at the same time the bed-roll 33 is brought into position to coöperate with the working cylinder 31. At the same time as the rocker-

frames 23 move about their pivots the gear 30 leaves the gear 19 and meshes with the gear 18 and is moved thereby in the opposite direction to feed the hide upon the hide-supporting roll 28 outward or toward the operator, while the working cylinder 31 is revolving rapidly at a high rate of speed in the direction indicated by the arrow in Fig 4 to operate upon the hide. When the operator has depressed the treadle into the position shown in Fig. 4, the radius-arm 43 assumes a position substantially perpendicular with the roller 46, resting upon a flat portion of the cam-plate 51, and thereby causes the rocker-lever 23 to be held firmly in rigid position, 70 with the rubber bed-roll 33 coöperating with the working cylinder, and is maintained in this position without strain upon the operator until pressure is removed from said treadle when the counterweight 56 will operate to move said rocker-levers 23 toward the operator, and thereby cause the rollers 46 to move toward the rear of the cam-plate 51, to permit the parts described to assume their normal position.

90 The counterweight 56 is mounted on a lever 57, pivoted at 58, said lever being provided with a short arm 59, extending in opposite direction to the main lever 57, and is connected by a link 60 to the rocker-levers 23. The connector 60 is made adjustable to vary the relative positions of said counterweight and levers. The radius-arm 43 is also made adjustable to vary the relative positions of said rocker-levers 23 and the cam-plate 51. 95 In the position shown in Fig. 2 the tendency of the weight 56 is to drop and cause the lever 23 to be moved into the position shown in Fig. 3. This movement of the lever 23 is, however, prevented by means of the radius-arm 43, which at that time has its roller 46 in a depression in the cam 51, the resistance being such as to overcome any tendency of the weight 56 to drop and move the lever 23 until the operator depresses the treadle 50 and moves the roller 46 out of the depression in the cam 51 and moves it into the position shown in Fig. 3, when the radius-arm 43 will 100 be in practically a vertical position and lock the lever 23, with its bed-roll 33, in position to coöperate with the hide-working cylinder 31. In reaching this position the weight 56 has been carried beyond a vertical line drawn through the pivot of its supporting-arm and is held in that position as long as 105 the operator retains his foot upon the treadle and keeps the roller 46 in the position shown in Fig. 3. As soon, however, as the operator removes his foot from the treadle the tendency of the weight 56 would be to move into 110 a position immediately below the pivot 13, and in so doing the upper end of the radius-arm 46 would be moved toward the front of the machine, bringing said radius-arm into 115 an inclined position and allowing the roller 120 125

46 to pass down the inclined cam 51 to regain its normal position, as indicated in Fig. 2. It is obvious, therefore, that the weight when on either side of the pivot of its supporting-arm 5 tends to move the bed-roll into coacting position and out of coacting position, as the case may be.

The boxes 3738, in which the feed-rolls 39 40 revolve, are mounted in frames 61, pivoted at 10 62 to the side frames 10, and are adapted to be, moved out of position to coöperate with the hide-supporting roll 28 and clamped in adjusted position by bolts 63.

When the hide is in soak and has hair on, it 15 is a great advantage to feed the hide without wrapping the same around the hide-supporting roll 28, and to accomplish this the feed-roll 40 is thrown out of contact therewith, and the feed-roll 39 being at right angles with a line drawn between the axis of said roll and said bed-roll feeds the hide without wrapping the same around the roll, and therefore permits the hide to be spread much more readily 20 than it otherwise would be, preventing any injury of the hide when it is fed between the bed-roll and working cylinder.

By means of this construction a machine for operating upon hides is provided of very simple construction and without springs, toggle mechanism, and expensive gearing, which 30 is liable to get out of order and prevent a proper operation upon the hides.

The stud 16 is made of sufficient length to permit the gear 19 to be moved lengthwise 35 thereof out of mesh with the gear 18, when the machine will operate without revolving the hide-supporting roll 28 except when the hide is being operated upon. The gear 19 is held in its different positions by means of cotter-pins, between which it revolves.

The cam-plate 51 is pivoted at one end at 70 to the side frame 10 and is provided at its opposite end with a slot 71, through which said plate may be clamped in various positions 45 about said pivot 70 by means of a clamping-bolt 72. This adjustment of the cam-plate 51 allows for a variation in the action of the rocker-frames and other parts in an obvious manner.

50 Having thus described my invention, I claim—

1. The combination with a working cylinder, of a feed-roll located above the upper surface of said cylinder, a pivoted frame, a hide-supporting roll and a freely-revoluble bed-roll 55 both having bearings in said frame at some distance from the pivot thereof, a yielding surface interposed between said bed-roll and said working cylinder and moved by said bed-roll, and means for moving said pivoted frame to cause said bed-roll to coöperate with said working cylinder and said hide-supporting roll to move toward said feed-roll into position to coöperate therewith.

60 2. The combination with a working cylin-

der, of a feed-roll located above the upper surface of said cylinder, a pivoted frame, a hide-supporting roll and a freely-revoluble rubber-covered bed-roll both having bearings in said pivoted frame at some distance from the pivot thereof, and means for moving said pivoted frame to cause said bed-roll to coöperate with said working cylinder and said hide-supporting roll to move toward said feed-roll into position to coöperate therewith. 70 75

3. The combination with a working cylinder, of a feed-roll located above the upper surface of said cylinder, a pivoted rocker-frame, a secondary frame pivoted to said rocker-frame, a hide-supporting roll and a rubber-covered bed-roll mounted in said secondary frame, means for moving said frames about their pivots to cause said bed-roll to coöperate with said working cylinder and said hide-supporting roll to move toward said feed-roll to coöperate therewith, and means for limiting the movement of said secondary frame about its pivot. 80 85

4. The combination with a working cylinder, of a pivoted frame, a hide-supporting roll 90 and a rubber-covered bed-roll both having bearings in said pivoted frame at some distance from the pivot thereof, means for moving said bed-roll freely about its axis independently of the other rolls until in a position to coöperate with said working cylinder, and means for rotating said bed-roll when coöperating with said working cylinder so that their coöperating surfaces will be moved in opposite directions. 95 100

5. The combination with a working cylinder, of a pivoted frame, a hide-supporting roll and a rubber-covered bed-roll both having bearings in said pivoted frame at some distance from the pivot thereof, means for moving said bed-roll freely about its axis independently of the other rolls until in position to coöperate with said working cylinder, means for rotating said bed-roll when coöperating with said working cylinder so that their coöperating surfaces will be moved in opposite directions, and a yielding device for moving said pivoted frame about its pivot and said bed-roll into position to coöperate with said working cylinder. 105 110 115

6. The combination with a working cylinder of a frame pivoted to the framework of the machine, a hide-supporting roll and a rubber-covered bed-roll pivoted in bearings movable with the free end of the pivoted frame, means permitting said bed-roll to freely move about its axis, means for moving said pivoted frame into position for said bed-roll to coöperate with said working cylinder, means for rotating said bed-roll when coöperating with said working cylinder so that their coöperating surfaces will be moved in opposite directions, and a yielding device operating upon said pivoted frame to insure contact between said support and said working cylinder. 120 125 130

7. The combination with a working cylinder, of a pivoted rocker-frame, a secondary frame pivoted to said rocker-frame, a rubber-covered bed-roll mounted in the free end of said secondary frame, means for moving said rocker-frame about its pivot, and a radius-arm connecting said secondary frame to a stationary part.
8. The combination with a working cylinder, of a pivoted rocker-frame, a secondary frame pivoted to said rocker-frame, a rubber-covered bed-roll adjustably mounted in said secondary frame at some distance from its pivot, treadle mechanism for moving said rocker-frame about its pivot, and a radius-arm connecting said secondary frame to a stationary part.
9. The combination with a working cylinder, of a pivoted rocker-frame, a secondary frame pivoted to said rocker-frame, arms adjustably secured to said secondary frame, a rubber-covered bed-roll mounted in the free end of said arms, and means for moving said rocker-frame about its pivot.
10. The combination with a working cylinder, of a pivoted rocker-frame, a secondary frame pivoted to said rocker-frame, the pivots of said frames being parallel, a rubber-covered bed-roll adjustably mounted in said secondary frame at some distance from its pivot, and mechanism for moving said rocker-frame about its pivot.
11. The combination with a working cylinder, of a hide-supporting roll, means for moving said roll in a direction to feed the hide toward the working cylinder when the former is not in operative position, a rubber-covered bed-roll, means for moving said bed-roll to bring it into contact with said knife-cylinder, and means for moving said hide-supporting roll so as to feed the hide away from the working cylinder when the latter is coöperating with said bed-roll.
12. The combination with a working cylinder, of a rubber-covered bed-roll, a hide-supporting roll, means for moving the hide-supporting roll in a direction to feed the hide toward the knife-cylinder when the latter is not in operative position, means for moving the same in the opposite direction when the working cylinder is coöperating with said bed-roll, and means for bringing said bed-roll and working cylinder into coöperating position.
13. The combination with a working cylinder, of a rubber-covered bed-roll, a hide-supporting roll, means for rotating said roll in one direction during the operation of the working cylinder, and means for moving the same in the opposite direction when the working cylinder is not in operation.
14. The combination with a working cylinder, of a pivoted rocker-frame, a secondary frame pivoted to said rocker-frame, a hide-supporting roll and a rubber-covered bed-roll mounted in said secondary frame, and means

for moving said frame about its pivot to cause said bed-roll to coöperate with said working cylinder.

15. The combination with a working cylinder, of a pivoted rocker-frame, a secondary frame pivoted to said rocker-frame, a hide-supporting roll and a rubber-covered bed-roll mounted in said secondary frame, means for moving said frame about its pivot to cause said bed-roll to coöperate with said working cylinder, and a yielding device secured to said rocker-frame serving to move said rocker-frame about its pivot to insure contact between said bed-roll and said working cylinder.

16. The combination with a working cylinder, of a pivoted rocker-frame, a secondary frame pivoted to said rocker-frame, a hide-supporting roll and a rubber-covered bed-roll mounted in said secondary frame, means for moving said frame about its pivot to cause said bed-roll to coöperate with said working cylinder, a yielding device secured to said rocker-frame serving to move said rocker-frame about its pivot to insure contact between said bed-roll and said working cylinder, and adjustable means for limiting the movement of said pivoted frames.

17. The combination with a working cylinder, of a pivoted rocker-frame, a secondary frame pivoted thereto, a hide-supporting roll and a rubber-covered bed-roll mounted in said secondary frame, means for moving said rocker-frame about its pivot, and a radius-arm connecting said secondary frame to a stationary part.

18. The combination with a working cylinder, of a pivoted rocker-frame, a secondary frame pivoted thereto, a hide-supporting roll and a rubber-covered bed-roll mounted in said secondary frame, a treadle mechanism for moving said rocker-frame about its pivot, and a radius-arm connecting said secondary frame to a stationary part.

19. The combination with a working cylinder, of a rubber-covered bed-roll, a hide-supporting roll, means for moving said bed-roll into position to coöperate with said working cylinder, a feed-roll, a gear secured to and revolving with said hide-supporting roll, two gears revolving in opposite directions, and means for moving said hide-supporting-roll gear from a position meshing with one of said gears to a position meshing with the other.

20. The combination with a working cylinder, of a pivoted frame, a secondary frame pivoted thereto, a hide-supporting roll and a rubber-covered bed-roll mounted in said secondary frame, means for moving said bed-roll into position to coöperate with said working cylinder, a pivoted lever, a connector between said lever and said pivoted frame, and a weight secured to the opposite end of said lever.

21. The combination with a working cylinder, of a pivoted frame, a hide-support pivoted to the free end of said frame, the pivots

of said frame and hide-support being parallel, means for moving said support into position to coöperate with said working cylinder, a pivoted lever, a weight upon one arm of said lever, and a connector between the other arm of said lever and a connector between the other arm of said lever and said pivoted frame adapted to assist in the movement of said hide-support toward the working cylinder and to start the hide-support in the oposite direction when pressure is removed from the treadle.

22. The combination with a working cylinder, of a pivoted rocker-frame, a secondary frame mounted in said rocker-frame, the pivots of said frames being parallel, a hide-support mounted in said secondary frame, means for moving said frames about their pivots to cause said hide-support to coöperate with said working cylinder, a pivoted lever, a weight upon one arm of said lever, and a connector between the other arm of said lever and said pivoted rocker-frame adapted to assist in the movement of said hide-support toward the working cylinder and to start the hide-support in the opposite direction when pressure is removed from the treadle.

23. The combination with a working cylinder, of a pivoted rocker-frame, a secondary frame mounted in said rocker-frame, a hide-supporting roll and a rubber-covered bed-roll mounted in said secondary frame, means for moving said frames about their pivots to cause said hide-supporting roll to coöperate with said working cylinder, a pivoted lever, a weight upon said lever, and a connector between said lever and said pivoted rocker-frame.

24. The combination with a working cylinder, of a pivoted rocker-frame, a secondary frame pivoted to said rocker-frame, a hide-supporting roll and a rubber-covered bed-roll having bearings in said secondary frame, means for moving said frames about their pivots to cause said hide-supporting roll to coöperate with said working cylinder, and means for limiting the movement of said secondary frame about its pivot.

25. The combination with a working cylinder, of a pivoted rocker-frame, a secondary frame pivoted to said rocker-frame, a rubber-covered bed-roll mounted in said secondary frame, and an arm one end of which is secured to said secondary frame and the other end of which is secured to a stationary part and adapted to regulate the movement of said secondary frame.

26. The combination with a working cylinder, of a pivoted rocker-frame, a secondary frame pivoted thereto, a hide-supporting roll and a rubber-covered bed-roll mounted in said secondary frame, treadle mechanism for moving said rocker-frame about its pivot, an arm one end of which is secured to said secondary frame and the other end of which is secured to a stationary part, a pivoted lever, a weight

upon said lever, and a connector between said lever and said rocker-frame.

27. The combination with a working cylinder, of a pivoted rocker-frame, a secondary frame pivoted to said rocker-frame, a hide-supporting roll and a rubber-covered bed-roll mounted in said secondary frame, means for rotating said hide-supporting roll in two directions, and means for moving said rocker-frame toward said working cylinder and at the same time change the inclination of said secondary frame to said rocker-frame.

28. The combination with a working cylinder, of a pivoted hide-support, means for moving said hide-support into position to coöperate with said working cylinder, a pivoted lever, a weight adjustable on said lever, and a connector between said lever and said hide-support and articulated to each.

29. The combination with a working cylinder, of a pivoted hide-support, means for moving said hide-support into position to coöperate with said working cylinder, a pivoted lever, a weight adjustable on said lever, and an adjustable connector between said lever and said hide-support and articulated to each.

30. The combination with a working cylinder, of a pivoted hide-support, means for moving said hide-support into position to coöperate with said working cylinder, a two-armed lever, a weight upon one of said arms, and a connector between the other arm and said hide-support and articulated to each.

31. The combination with a working cylinder, of a pivoted hide-support, an adjustable radius-arm secured to said hide-support, a roller in the end of said radius-arm, a pin therefor, a cam to coöperate with said radius-arm, a rocker-shaft, an arm on said rocker-shaft, and a slot in said arm engaging with said roller-pin.

32. The combination with a working cylinder, of a pivoted hide-support, a fixed cam, a connector between said hide-support and said cam, means for moving said connector along said cam to move said hide-support into position to coöperate with said working cylinder, a two-armed pivoted lever, a counterweight upon one arm of said lever, and a connector between the other arm and said hide-support.

33. The combination with a working cylinder, of a pivoted rocker-frame, a hide-supporting roll mounted in the free end of said rocker-frame, a driving-shaft, a gear driven by said driving-shaft, a second gear driven by said driving-gear, a gear upon the shaft of said hide-supporting roll, and means for moving said latter gear from mesh with one of the before-mentioned gears into mesh with the other of said gears.

34. The combination with a working cylinder, of a pivoted rocker-frame, a secondary frame pivoted to the free end of said rocker-frame, the pivots of said frames being paral-

- lel, a rubber-covered bed-roll mounted in bearings in said secondary frame, a pivoted lever, a weight adjustable on said lever, and a connector between said lever and said pivoted 5 rocker-frame.
35. The combination with a working cylinder, of a pivoted rocker-frame, a secondary frame pivoted to the free end of said rocker-frame, the pivots of said frames being parallel, a rubber-covered bed-roll mounted in bearings in said secondary frame, a pivoted lever, a weight adjustable on said lever, and an adjustable connector between said lever and said pivoted rocker-frame.
- 10 36. The combination with a working cylinder, of a pivoted rocker-frame, a secondary frame pivoted to the free end of said rocker-frame, the pivots of said frames being parallel, a rubber-covered bed-roll mounted in bearings in said secondary frame, a two-armed lever, a weight upon one of said arms, and a connector between the other arm and said rocker-frame.
- 15 37. The combination with a working cylinder, of a pivoted rocker-frame, a secondary frame pivoted to the free end of said rocker-frame, a rubber-covered bed-roll mounted in bearings in said secondary frame, a radius-arm secured to said secondary frame, a cam 20 to coöperate with said radius-arm, and means for moving said radius-arm along said cam to move said bed-roll into position to coöperate with said working cylinder.
- 25 38. The combination with a working cylinder, of a pivoted rocker-frame, a secondary frame pivoted to the free end of said rocker-frame, a rubber-covered bed-roll mounted in bearings in said secondary frame, a radius-arm secured to said secondary frame, a roller in 30 the end of said radius-arm, a cam to coöperate with said radius-arm, and means for moving said radius-arm along said cam to move said bed-roll into position to coöperate with said working cylinder.
- 35 45. 39. The combination with a working cylinder, of a pivoted rocker-frame, a secondary frame pivoted to the free end of said rocker-frame, a rubber-covered bed-roll mounted in bearings in said secondary frame, an adjustable radius-arm secured to said secondary frame, a roller in the end of said radius-arm, a cam to coöperate with said radius-arm, and means for moving said radius-arm along said cam to move said bed-roll into position to coöperate with said working cylinder.
- 40 55. 40. The combination with a working cylinder, of a pivoted rocker-frame, a secondary frame pivoted to the free end of said rocker-frame, a rubber-covered bed-roll mounted in bearings in said secondary frame, an adjustable radius-arm secured to said secondary frame, a roller in the end of said radius-arm,
- a cam to coöperate with said radius-arm, a rocker-shaft, a treadle on said rocker-shaft, and an arm secured to said rocker-shaft and 65 operating upon said radius-arm to move it along said cam.
41. The combination with a working cylinder, of a pivoted rocker-frame, a secondary frame pivoted to the free end of said rocker-frame, a rubber-covered bed-roll mounted in bearings in said secondary frame, an adjustable radius-arm secured to said secondary frame, a roller in the end of said radius-arm, a pin therefor, a cam to coöperate with said 70 radius-arm, a rocker-shaft, an arm on said rocker-shaft, and a slot in said arm engaging with said roller-pin.
42. The combination with a working cylinder, of a pivoted rocker-frame, a secondary frame pivoted to the free end of said rocker-frame, a rubber-covered bed-roll mounted in bearings in said secondary frame, a fixed cam, a connector between said rocker-frame and said cam, means for moving said connector 75 along said cam to move said bed-roll into position to coöperate with said working cylinder, and a counterweight secured to said rocker-frame assisting in its movement toward said working cylinder.
43. The combination with a working cylinder, of a pivoted rocker-frame, a secondary frame pivoted to the free end of said rocker-frame, a rubber-covered bed-roll mounted in bearings in said secondary frame, a fixed cam, 80 a connector between said rocker-frame and said cam, means for moving said connector along said cam to move said bed-roll into position to coöperate with said working cylinder, a two-armed pivoted lever, a counterweight upon one arm of said lever, and a connector between the other arm and said rocker-frame.
44. The combination with a working cylinder, of a pivoted hide-support, a radius-arm secured to said hide-support, a roller in the 85 end of said radius-arm, a cam to coöperate with said radius-arm, and means for varying the relative position of said cam to said radius-arm.
45. The combination with a working cylinder, of a pivoted hide-support, a radius-arm secured to said hide-support, a roller in the end of said radius-arm, a pivoted cam to coöperate with said radius-arm, and means for 90 varying the position of said cam about said pivot.
